UNITED STATES PATENT OFFICE.

A. C. BROWNELL, OF BROOKLYN, NEW YORK.

IMPROVEMENT IN COPPER BOILERS.

Specification forming part of Letters Patent No. 39,881, dated September 15, 1863.

To all whom it may concern:

Be it known that I, A. C. BROWNELL, of Brooklyn, in the county of Kings and State of New York, have invented a new and useful Improvement in the Construction of Copper Water-Heaters; and I do hereby declare that the following is a full, clear, and exact description of the same, reference being had to the accompanying drawings, making a part of this specification, in which—

Figure 1 is a longitudinal central section of a heater constructed according to my invention, *xx*, Fig. 2, indicating the plane of section; Fig. 2, an external view of the same.

Similar letters of reference indicate corresponding parts in the two figures.

This invention relates to an improvement in the construction of copper water-heaters, such as are applied to or connected with cooking ranges and stoves. All copper heaters heretofore made have been constructed with composition or copper heads, or ends, and fastened to the cylinder or body of the heater by the copper being turned over these heads or ends, and made water-tight by the use of soft solder, and the heater becoming sometimes intensely hot and then cooling off, expansion and contraction occur to such a degree that the soft solder and copper not yielding or expanding alike causes the soft solder to yield or peel off, and the heater thereby becomes leaky and unfit for use.

My invention and improvement consist in so constructing the heater that the two ends or heads are entirely brazed in, as are also the spuds for the couplings of the pipes, thereby producing a heater with every seam or joint brazed, and made perfectly durable and watertight without the use of soft solder.

To enable those skilled in the art to fully understand and construct my invention, I will proceed to describe it.

A represents the body or main portion of a copper heater, which body is of cylindrical form, and is connected at its edges by brazing, as shown at *a*, Fig. 2.

B B' represent the end pieces of the heater, which may be of dome shape. These end pieces are connected to the body A by brazing, as shown at *b*, Fig. 2. The upper end piece, B, has the cold and hot water pipes C C'

attached to it in the usual way. The pipe D, at the bottom or lower end piece, B', is attached in a novel way, as follows: The end piece B' has a large circular hole, *c*, made in it, around which hole there is a pendent flange, *d*, having a screw cut on its exterior to admit of a cap, E, being screwed upon it. This cap E is provided with a pendent tube, *e*, on which a box or socket, F is, screwed, which secures the pipe D to the tube *e*, as shown clearly in Fig. 1. This arrangement of the cap E and pipe D is the essential feature of the invention, for by it I am enabled to secure the ends of the heater to the body by means of brazing.

Brazing, as is well known to coppersmiths and metal-workers generally, can only be performed at quite a high heat, which oxidizes the copper, and renders it necessary to polish the same after the operation of brazing has been performed. This polishing, or "planishing," as it is technically termed, is accomplished by hammering, and in order to effect this it is necessary to introduce within the heater an instrument to serve the office of an anvil on which to pound the copper. The hole *c* in the lower end piece, B', admits of this, and after the brazing process is accomplished the hammering or planishing may be performed without any difficulty whatever. Thus I obtain a copper heater having all its joints or seams brazed, and consequently permanently secured together. The spuds *a* for the pipe-couplings are also brazed to the heater. The ordinary copper heaters have their end pieces attached or secured to the body or main portion by means of soft solder in consequence of no plan having been hitherto devised to admit of the planishing of the finished heater after brazing.

It will be understood that the bodies or main portions of the ordinary copper heaters have their seams brazed, and are then polished or planished, and the end pieces are planished separately and attached by soft solder, which does not, of course, oxidize the metal or injure the planished surface.

Having thus described my invention, I claim as new and desire to secure by Letters Patent—

1. As an improved article of manufacture, a copper water-heater constructed in the man-

ner substantially as herein shown and described.

2. The manner by which I produce or manufacture this heater with the application of what may be called a "double coupling"—to wit, the cap E, tube e, and socket F—the use of which enables me to completely braze all the

seams or joints of the heater, and also to planish or hammer the same when brazed, thereby perfecting the heater, as set forth.

A. C. BROWNELL.
